THEIR ATTORNEY.

UNITED STATES PATENT OFFICE.

JOHN C. COX AND BERTHOLD V. COX, OF ST. LOUIS, MISSOURI.
DISINFECTANT-DISPENSING ATTACHMENT FOR FLUSH-TANKS.

1,220,398.

Specification of Letters Patent. Patented Mar. 27, 1917.
Application filed July 1, 1916. Serial No. 107,101.

To all whom it may concern:

Be it known that we, JOHN C. COX and BERTHOLD V. COX, citizens of the United States, and residents of St. Louis, Missouri, § have invented certain new and useful Improvements in Disinfectant-Dispensing Attachments for Flush-Tanks, of which the following is a specification containing a full, clear, and exact description, reference being 10 had to the accompanying drawings, forming a part hereof.

Our invention relates to an improved disinfectant dispensing attachment for flush tanks, and consists in the novel arrangement 15 and combination of parts hereinafter described and specifically pointed out in the claim hereunto appended.

One of the objects of our invention is to provide an improved device for automatically delivering to the flush-tanks of closets, urinals and the like a suitable quantity of liquid disinfectant, or germicide, each time the flush-tank is filled or emptied, whereby the water used for flushing will be supplied 20 with a proper amount of disinfectant and germicide just after said tank has been discharged and refilled, thus holding in readiness for use within said tank a body of water with which is mixed the disinfectant or 25 germicide, and permitting the bowl of the closet, or the urinal, to be thoroughly disinfected each time the flushing operation takes place.

A further object of our invention is to 5 provide improved means for mixing a liquid disinfectant or germicide with the water contained in the flush-tank as soon as said tank is refilled after it has been discharged, and for maintaining in said tank such body of disinfected water as long as said tank remains in its normal filled condition, whereby the said body of disinfected water will act as a deodorizer and germicide for the air of the room.

In the drawings:

Figure 1 is a vertical section of a portion of a common flush-tank having our invention applied thereto, and with the parts in position as they appear after a flushing operation has taken place.

Fig. 2 is a detail horizontal-section, taken through the disinfectant-valve stem and its casing.

The numeral 1 indicates the usual flush-tank, for flushing a closet-bowl or urinal,

the same being supplied with ordinary and well-known means for keeping it filled with water,—that is, with a common float-controlled valve connected to the source of water-supply (not shown).

In the present illustration of our invention, we locate the disinfectant or germicide tank 2 above the said flush-tank 1, and support the same upon the cover 3 of the said flush-tank, but it should be clear that we can 65 support the said disinfectant-tank in any other known way, as by merely hanging it upon the wall at a point above the said flush-tank.

Said disinfectant-tank 2 is provided with 70 a top 4 and a filling cap 5, and from said top rises a vertical bracket 6, to the upper end of which is pivoted a lever 7.

A vertical rod 8 has its upper end pivotally connected to one end of the said lever 7 75 by means of a suitable pin or bolt 9, and the lower end of the said vertical rod is connected to the disinfectant-valve 10 by means of an eye 11.

Said disinfectant-valve is provided with a 80 conical seat in the upper end of a disinfectant measuring-chamber 12, which passes downwardly through openings in the bottom of the said disinfectant-tank and in said flush-tank cover 3, so that said measuring-chamber will extend a considerable distance 85 within the said flush-tank 1.

Suitable packing-washers 13 and a common clamp-nut 14 are made use of, as shown, to form a tight joint at the point where said 90 measuring-chamber passes through the bottom of the said disinfectant tank.

The numeral 15 indicates a clamp-nut on said measuring-chamber beneath said flush-tank cover 3, for holding the said parts in 95 relative position.

Mounted at the lower end of the said measuring-chamber is a common valve 16, for controlling the exit-opening 17 of the said measuring-chamber.

Said exit-valve 16 is provided with the usual guide 18 for its stem 19, and said stem is connected to a common float 20 by means of the usual levers 21, 22 and brackets 23, 24, so that whenever the said float is 105 raised by the rise of water in the said flush-tank the said valve will be opened, and be held open as long as the level of the water in said tank remains sufficiently high.

The numeral 25 designates a vertical rod 110

whose function is to loosely connect the float-arm 26 to the said lever 7, and permit a certain amount of "play" or lost motion between the said parts.

The lower end of the said vertical rod 25 is provided with an integral hook or eye 27 which engages the walls of a slot 28 formed in the said float-arm 26.

In the present case, the said vertical rod 25 passes through a guide-opening 29 formed in the said flush-tank cover 3.

The upper end of the said vertical rod 25 is threaded, and is provided with an adjustable nut 30, and said rod passes loosely through an opening 31 formed in the free end of the said lever 7.

A projection 32 is fixed on the said vertical rod 25, to contact with the underside of the said lever.

20 The operation is as follows:
The normal position of the parts is that in which they are shown. The flush-tank should be filled sufficiently full of water to keep the said float 20 elevated and the disinfectant exit-opening 17 of the said measuring-chamber open and in free communication with the water in said flush-tank, in which position any disinfectant which might be contained in said measuring-chamber would pass into and freely mingle with the water of said tank, and cause said water to act as a disinfectant and deodorizer for the air of the room in which said tank is located.

35 The disinfectant tank 2 should, of course, be supplied with a suitable quantity of any approved or well-known liquid disinfectant or germicide.

Whenever the said flush-tank is discharged, in flushing the closet-bowl, urinal 40 or the like, the said float 20 falls, and carries with it its arm 26, which through the action of the levers 21, 22, closes the disinfectant-exit 17 by its valve 16; and such action takes place prior to the opening of the disinfectant valve 10.

45 As the float 20 continues to fall, the said vertical rod 25 passes downward until its nut 30 comes in contact with the adjacent end of the disinfectant-valve lever 7, and depresses said end of such lever, carrying its opposite end (together with the said vertical valve-rod 8 and valve 10) upwardly, thus opening the said disinfectant-valve, and permitting a definite quantity of disinfectant to 55 run into the said measuring-chamber 12, whence it will be discharged as before, upon the refilling of the said flush-tank with water.

60 The stem 19' of the said valve 10 is made non-cylindrical as shown in Fig. 2, to facilitate the passage of disinfectant past said stem. The said stem 19' of the said disinfectant-valve 10 is made quite long, so that as 65 the valve works up and down in its guide 18' at the upper end of the said measuring-

chamber 12, it will be guided in such movement, no matter how great the movement may be.

As the water rises in filling the said flush-tank, (with the parts in the position in which they are shown in Fig. 1) the said float-rod nut 30 will release the adjacent end of the disinfectant-valve lever 7, and the said valve 10 will close, cutting off the further passage of disinfectant to the said measuring-chamber 12, and then the said exit-valve 16 will be opened, permitting the disinfectant carried within said chamber to make its exit therefrom and mingle with the water contained in said flush-tank, and be 80 in readiness for another flushing operation.

The water in the flush-tank will act as a deodorant for the air of the room, in addition to thoroughly disinfecting the closet-bowl, or urinal, or other thing into or upon 85 which it may be discharged. The said flush-tank cover 3, in order to permit the odor of the disinfected water to pass into the room, should of course be open or partly cut away.

Our improved disinfectant dispenser is 90 very economical in the use of the liquid disinfecting-material, as it wastes none of it.

We do not limit ourselves to the exact construction shown in the drawings, as it is obvious that such changes can be made by 95 skilled mechanics as are legally within the scope of our invention.

For instance, various materials may be made use of in practicing our invention, and the size and proportions of the various parts 100 may be changed, all without departing from the spirit of our invention.

We claim the following as our invention:

An improved disinfectant dispensing-attachment for flush-tanks, consisting of the 10 combination with a flush-tank, of a disinfectant tank arranged above said flush-tank, a vertical bracket rising from the top of said disinfectant-tank, a horizontal lever pivotally mounted at the upper end of said bracket, a disinfectant measuring-chamber extending vertically from the bottom of said disinfectant-tank a considerable distance into the said flush-tank and having its interior in communication with both of said tanks, a disinfectant-valve having a long non-cylindrical stem which is mounted to slide in the upper part of the said measuring-chamber, to control the passage of a liquid disinfectant to the said measuring-chamber, a vertical rod connecting said valve to the adjacent end of said horizontal lever, an exit-valve at the lower end of said measuring-chamber, for controlling the passage of disinfectant from the latter, a common float and connections located in said flush-tank, for automatically opening said exit-valve as the water rises in said flush-tank, and for automatically closing the same when the water in said flush tank is discharged,

said float having an arm that is slotted, a vertical rod extending from the slot in said float-arm upwardly to the overhanging end of the said horizontal lever, and connecting 5 said float-arm to said lever, the upper portion of the said last-mentioned vertical rod being threaded, and the threaded portion thereof passed loosely through an opening formed in the adjacent end of the last-mentioned vertical rod, an adjusting-nut on said threaded portion above said horizontal lever, and a fixed stop on said last-mentioned ver- 10

tical rod, to contact with the underside of said horizontal lever as the said float and float-arm rise.

15

In testimony whereof we have signed our names to this specification, in the presence of two subscribing witnesses.

JOHN C. COX.
BERTHOLD V. COX.
